UNITED STATES PATENT OFFICE.

GEORGE W. JARMIN, OF CORPUS CHRISTI, TEXAS.

LANTERN.

SPECIFICATION forming part of Letters Patent No. 530,049, dated November 27, 1894.

Application filed August 29, 1894. Serial No. 521,627. (No model.)

To all whom it may concern:

Be it known that I, GEORGE W. JARMIN, a citizen of the United States, residing at Corpus Christi, in the county of Nueces and State of Texas, have invented certain new and useful Improvements in Lanterns, of which the following is a specification.

This invention relates to a lantern of that class covered by my Letters Patent No. 522,062, dated June 26, 1894, and has for its object to simplify the construction of said patented device and provide a more convenient and readily actuated means for retaining the chimney upon the base of the lantern.

15 The invention consists of a lantern having a base to which is pivoted a main-bail which is of such length as to extend above the crown of the chimney placed within the same upon the base, said bail having hinged thereto a handle-bail for the purpose of carrying the lantern and the upper portions of the side wires of said main-bail forming guides for a retaining-device or wire, which at its outer ends is constructed with eyes to receive said side-wires, the retaining-device being normally pressed downward by means of spiral-springs coiled around said side-wires below the eyes to which the handle-bail is hinged.

20 In the accompanying drawings:—Figure 1 is a perspective view of my improved lantern. Fig. 2 is a vertical transverse section of the lower portion of the lantern, showing the same on a larger scale, and Fig. 3 is a horizontal sectional view on the line 3, 3, Fig. 1, showing the retaining-device or wire pressed into the notches of the crown of the chimney.

25 Similar letters of reference indicate corresponding parts.

Referring to the drawings, B represents the 30 base of my improved lantern, which is of circular form, provided with a downwardly-projecting circumferential flange b, and at its center with a raised circular portion b' onto which is soldered or otherwise secured the 35 central candle-socket b². The base is preferably made of an integral piece of sheet-metal which is struck or bent up in the form shown. The raised portion b' corresponds in shape and size to the lower part of the chimney or globe A, and the chimney is retained thereon in the manner to be hereinafter de-

scribed. The candle-socket b² may have a vertical slot b³ at one side, which is adapted to receive an implement for the purpose of removing the candle or a stump if desired. 55 At one side of the base is arranged a finger-loop b⁴, whereby the lantern may be carried in the hand the same as a lamp.

The lower bent ends C' of a main-bail C of wire are adapted to enter diametrically 60 opposite holes formed in the flange b of the base of the lantern so that said main-bail is thereby hinged to said base. The length of the main-bail C is such that the cross-piece or bridge C² of the same can, when the main-bail is locked in position, extend some distance 65 above the crown of the chimney A, the ends of said bridge C² where it joins the upper portions C³ of the main-bail being formed with eyes C⁴, which receive the eyes d of a U-shaped wire handle-bail D. The upper portions C³ of the side-wires of said main-bail are formed parallel with each other, while the lower portions of said side-wires diverge slightly outward so as to span the bulging 70 portion of the chimney. The object in arranging the upper portions C³ of the side-wires parallel is for the purpose of forming guides for a retaining-device or wire E which 75 at its outer ends is provided with eyes e through which said side-wires pass. The said eyes e are formed by a number of spiral coils 80 at the ends of the retaining-device, said coils being arranged closely together. By means of spiral springs F which are coiled around 85 the guide portions C³ of the side-wires, (said springs being arranged between the eyes C⁴ of the main-bail and the eyes e of the retaining-device,) the retaining-device is normally pressed downward so that it is caused 90 to engage in any diametrically opposite pair of notches a which are formed in the crown of the chimney A. It will be observed that by resting the palm of the hand upon the bridge C² a purchase may be obtained, so that 95 one or more fingers may be utilized to engage under and press upwardly against the retaining-device and overcome the action of the spiral springs, thereby releasing the retaining-device from the chimney and enabling 100 the same to be removed so that the candle such as g may be conveniently lighted.

The advantages of my improved lantern are as follows: first, it can be manufactured very cheaply for the reason that the base is stamped out of one integral piece of sheet metal; second, the whole device, without the chimney, can be stored in a very small compass by arranging the base B in line with the main-bail C; third, the retaining-device which is held on the main-bail may be very conveniently manipulated by means of one hand, so that the same may be disengaged from the chimney and may as readily be engaged with the same, so as to lock the chimney quickly in position after the candle has been lighted.

I do not desire to limit myself to the providing of a base with a candle-socket as shown, as it is evident without particular illustration that the base may be so constructed as to provide means for holding an oil-fount.

Having thus described my invention, I claim as new and desire to secure by Letters Patent—

1. In a lantern the combination of a base adapted to support a chimney thereon, a bail attached to said base and extending above the chimney, and a spring-actuated bar adapted to slide vertically on opposite arms of said bail and extending transversely across the top of the chimney, serving to automatically clamp said chimney and leave its top open, substantially as described.

2. In a lantern, the combination of a base adapted to support a chimney thereon, a bail attached to said base and extending above the chimney, a cross bar extending across the chimney and provided with eyes adapted to slide on said bail, and spiral springs interposed between the top of said bail and said cross bar for pressing the latter on the chimney top.

3. In a lantern, the combination of a base adapted to support a chimney thereon, a bail hinged to said base and provided at its upper ends with a cross piece having loops at its ends, a cross bar extending across the chimney top and provided with eyes adapted to slide on said bail, spiral springs interposed between said cross piece of the bail and the cross bar for pressing the latter on the chimney top, and a handle attached to said loops.

In testimony that I claim the foregoing as my invention I have signed my name in presence of two subscribing witnesses.

GEORGE W. JARMIN.
